UNITED STATES PATENT OFFICE.

JOSUA GABRIEL PAULIN, OF LANDSKRONA, SWEDEN.

METHOD OF ELECTROLYZING STREAMING ELECTROLYTES.

1,056,118.

Specification of Letters Patent.

Patented Mar. 18, 1913.

Application filed April 7, 1911. Serial No. 619,611.

To all whom it may concern:

Be it known that I, JOSUA GABRIEL PAULIN, a subject of the King of Sweden, residing at Landskrona, in the Kingdom 5 of Sweden, have invented new and useful Improvements in Methods of Electrolyzing Streaming Electrolytes, of which the following is a specification, reference being had to the drawing accompanying and forming a 10 part hereof.

This invention relates to an improved method of electrolyzing streaming electrolytes.

In technically using the methods of electrolyzing hitherto known, great difficulties are experienced by the fact that the products liberated at the anode or at the cathode, respectively, cannot be obtained sufficiently pure, without very complicated or expensive 20 apparatus being used.

The object of the invention is to make it possible to obtain pure products by effectively preventing any ion from passing from one electrode to the other.

25 The invention consists, chiefly, in either causing the whole electrolyte to move with a quite uniform speed (for instance by using a suitable porous plate or diaphragm of most homogeneous character) in the direction of the electric current, or opposite thereto, automatically controlling the said speed, and so arranging the electrodes that the current density will be the same in all parts of a section or layer of the electrolyte 30 at right angles to the direction of the electric current, or in causing parts of the electrolyte to move with a comparatively great speed, which need not be regulated, *i. e.* creating currents of liquid in the anode 35 chamber or the cathode chamber or both said chambers, which in this case must be separated by highly porous plates.

The invention further comprises certain novel features of proceeding and apparatus hereinafter more fully described and claimed.

40 In the drawing, I have shown diagrammatically certain electric apparatus and appliances adapted to be used in carrying the 50 invention into effect.

Figure I is a vertical section of a simple electrolytic cell adapted to be used in certain cases when the electrolyte is caused to move as a whole. Fig. II is a vertical sec-

tion of an electrolytic apparatus adapted to 55 be used for similar purposes. Fig. III is a diagram of a device for regulating the speed of movement of the electrolyte. Figs. IV and V are vertical sections of electrolytic apparatus adapted to be used for causing 60 separate currents of liquid to flow in the anode and the cathode chamber.

Referring to the drawing, the electrolytic apparatus shown in Fig. I is arranged horizontally and the electrolyte caused to flow 65 from the bottom upward, for instance from the cathode 1 to the anode 2. The whole electrolyte is caused to move with a quite uniform speed, disturbing currents of liquid being prevented by the vessel having one or 70 more narrow parts 3 or by the provision of one or more porous partitions or diaphragms. The quantity of anode product in a certain layer near the cathode is preferably controlled by an electrolytic regulating device based on the variations in the resistance or the tension of decomposition 75 respectively effected for instance by changes in the osmotic pressure of the electrodes or the pressure by which the ions are caused 80 to move in the solution. By this means the important result is gained that the cations between the electrodes may be made practically stationary relatively to the electrolytic cell if at the same time the current 85 density is equally uniformly distributed as the flow of liquid, whereas the anions obtain a greater speed than the absolute traveling speed so that the electricity is transported between the electrodes through the 90 anions only.

As an example I will now describe in what manner the electrolysis of zinc sulfate may be performed. The apparatus to be employed may be constructed as shown in 95 Fig. II. It comprises a preferably cylindrical vessel *a* of clay or other suitable material and having a hollow bottom *b*, the inner part *c* of which is perforated all over its surface. The solution of zinc sulfate is 100 supplied at the bottom through a pipe or tube 4 and allowed to spread uniformly along the horizontal cathode 5, then passes a porous plate 6 and the anode 7 and runs off through an overflow tube 8. The speed of the liquid 105 is regulated in such a manner that a small part of the total flow of liquid is removed through a tube 9 and caused to pass through

a regulating device of the kind set forth, for instance an electrolytic cell having one electrode of platinum and one electrode of zinc and containing crystals of potassium dichromate. An electric current of a certain strength is caused to flow from an element A (Fig. III) through the cell C. When the percentage of acid is below a certain limit, a layer of zinc is deposited on the platinum. The variations in strength of the current through a relay V connected in shunt to the cell C may be used for regulating the supply of fresh electrolyte to the electrolyzer.

It is obvious that any suitable regulating device may be used but I prefer to use an electrolytic regulator of the kind set forth. It has been found that, if the percentage of sulfuric acid of the liquid flowing through the cell C sinks below a certain limit (0.25 per cent. at a current density in the cell of about 1.5 amperes per square decimeter), the electromotive force suddenly decreases with one volt causing a sudden change of the current strength through the relay V, which on account thereof closes or opens an electric circuit for a strong current acting to throttle or to open a valve for the supply of electrolyte. By this means the percentage of acid of the solution drawn off through the tube 9 is constantly kept at the said height (0.25 per cent.).

It is to be noted that it is not necessary to cause the electrolyte to move as a whole with a regulated speed, since as before stated similar results may be obtained by causing parts of the electrolyte to move with a comparatively great speed, which need not be regulated, *i. e.* by arranging separate currents of liquid in the anode chamber and the cathode chamber, either a current of fresh electrolyte in the anode chamber and a current of cathode product in the cathode chamber (for instance in electrolyzing NaCl) or a current of fresh electrolyte in the cathode chamber and a current of anode product in the anode chamber (for instance in electrolyzing ZnSO₄), said currents of liquid being preferably caused to flow in the direction of the electric current or in the direction opposite thereto. Also in this manner the traveling from the anode chamber to the cathode chamber or vice versa of ions which may have a disturbing influence on the process (the output, the purity of the products, etc.,) may be effectively prevented. The speed of the liquids need only be so great that the traveling of a certain ion to the anode or the cathode respectively is avoided. It has been proved that in such case the traveling of the said ion to the anode chamber or the cathode chamber respectively is prevented.

In order that my invention may be more fully understood I will now proceed to de-

scribe in what manner this modification of my improved process may be carried into effect.

Example 1—Electrolysis of zinc sulfate.—A concentrated solution of zinc sulfate is admitted under pressure at the bottom of the electrolyzer (Fig. IV), which may have the sides d and bottom e, f constructed as hereinbefore described with reference to Fig. II, caused to spread all over the horizontally extending cathode 11, for instance by a porous plate, a filter of sand or the like, and drawn off in a less concentrated condition through a tube 12. A small portion of the solution (for instance 1 per cent.) passes through the diaphragm 13 and escapes through a tube 14. By this means all diffusion of anode liquid into the cathode chamber is prevented. Sulfuric acid is admitted through a tube 15, passes through the perforated anode 16 and runs off in a more concentrated condition through the tube 17. A portion of the said acid passes through the diaphragm 18 and is drawn off through the tube 14. By this means all diffusion of cathode liquid into the anode chamber is prevented.

In the manner described the cathode is always kept surrounded by a concentrated, slightly acid solution of zinc sulfate, and the zinc precipitates uniformly and compactly. At the same time pure sulfuric acid of a varying concentration (for instance 60 per cent.) is obtained, without the resistance in the electrolyzer being too high.

Example 2—Electrolysis of sodium chlorid for producing caustic soda and chlorin.—The electrolytic apparatus may be arranged in substantially the same manner as that just described or in a vertical position (Fig. V). The solution of sodium chlorid is admitted through a tube 19 into a comparatively flat vessel having vertical side walls h, preferably rectangular in shape, passes the anode 20 and is (the main portion thereof) drawn off at 21 in a less concentrated condition, while a small portion of said solution passes through the diaphragm 22 and runs off through a tube 23. A solution of sodium hydroxid or caustic soda is admitted at 24, passes through the cathode 25, shown in the form of a wire net, and through a porous partition 26 and is drawn off through a tube 27 in a more concentrated condition, while a portion of said solution passes through the diaphragm 28 and escapes through the tube 23. In this manner pure caustic soda is obtained.

Example 3—Electrolysis of sodium sulfate.—In using the electrolytic apparatus shown in Fig. IV, the caustic soda formed in the cathode chamber is continuously removed by a current of caustic soda admitted through the tube 12 and drawn off through the tube 10 in a more concentrated condi-

tion. A small portion of caustic soda passes through the diaphragm 13. The solution of sodium sulphate is admitted through the tube 14, passes through the diaphragm 18 and runs off through the tube 17. The speed of movement of the solution through the diaphragm is controlled by a regulating device, for instance of the kind hereinbefore set forth. The solution drawn off through the tube 17 thus consists of almost entirely pure sulfuric acid.

I claim:

1. The method of electrolyzing streaming electrolytes which consists in causing a current of fresh electrolyte to flow toward and past one of the electrodes, and causing a solution of the product formed at the other electrode to flow toward and past the said latter electrode, substantially as and for the purpose set forth.

2. The method of electrolyzing streaming electrolytes which consists in arranging the electrodes in such a manner that the current density will be the same in all parts of a cross-section of the electrolyte, and causing the said electrolyte to move as a whole with an automatically controlled speed, substantially as and for the purpose set forth.

3. The method of electrolyzing streaming electrolytes which consists in arranging the electrodes in such a manner that the current density will be the same in all parts of a cross-section of the electrolyte, and causing the said electrolyte to move as a whole with an automatically controlled speed in a direction determined by the direction of the electric current.

4. The method of electrolyzing streaming electrolytes which consists in separating the anode chamber and the cathode chamber by porous partitions, causing a current of fresh electrolyte to flow through one of said chambers, and causing a current of a solution of the product formed in the other chamber to pass through the latter, substantially as and for the purpose set forth.

5. The method of electrolyzing streaming electrolytes which consists in separating the anode chamber and the cathode chamber by double partitions inclosing an intermediate chamber, and maintaining a somewhat lower pressure in the said intermediate chamber, substantially as and for the purpose set forth.

6. The method of electrolyzing streaming electrolytes which consists in arranging the electrodes in such a manner that the current density will be the same in all parts of a cross-section of the electrolyte, causing the said electrolyte to move as a whole, and controlling the speed of movement of the said electrolyte by causing a part thereof to pass through an electrolytic regulating device adapted to work by changes in the composition of the liquid admitted.

7. The method of electrolyzing streaming electrolytes which consists in separating the anode chamber and the cathode chamber by porous partitions, causing a current of fresh electrolyte to flow through one of said chambers, causing a current of a solution of the product formed in the other chamber to pass through the latter, and controlling the speed of movement of the fresh electrolyte by admitting a part thereof into an electrolytic regulating device adapted to work by changes in the composition of the electrolytic bath therein.

8. The method of electrolyzing streaming electrolytes which consists in separating the anode chamber and the cathode chamber by double partitions inclosing an intermediate chamber, maintaining a somewhat lower pressure in the said intermediate chamber, causing a current of fresh electrolyte to pass through one of said chambers, and causing a current of a solution of the product formed in the other chamber to pass through the latter.

9. The method of electrolyzing streaming electrolytes which consists in separating the anode chamber and the cathode chamber by double partitions inclosing an intermediate chamber, maintaining a somewhat lower pressure in the said intermediate chamber, causing a current of fresh electrolyte to pass through one of said chambers, causing a current of a solution of the product formed in the other chamber to pass through the latter, and controlling the speed of movement of the fresh electrolyte by admitting a part thereof into an electrolytic regulating device adapted to work by changes in the composition of the electrolytic bath therein.
